UNITED STATES PATENT OFFICE.

HENRY WEBB HYDE, OF NORTH COHASSET, MASSACHUSETTS, ASSIGNOR TO HYDE ENGINEERING COMPANY, OF BOSTON, MASSACHUSETTS, A CORPORATION OF MASSACHUSETTS.

SPRING SUSPENSION FOR VEHICLES.

Application filed May 28, 1923. Serial No. 641,933.

This invention relates to vehicle spring suspensions of the general type shown and described in my prior application for Letters Patent, filed September 29, 1921, Serial 5 No. 504,160.

As explained in said prior application, the invention disclosed therein consists primarily in providing the vehicle with longitudinal springs or spring reaches connected 10 at their ends, either directly or indirectly, with the axles, and in supporting the body on the spring reaches intermediate the ends of the latter in such a manner as to permit said body to rock freely, with respect to and 15 independently of the reaches, upon a horizontal, transverse axis, so that tilting or rocking of the reaches, caused by a vertical movement of either the front or rear wheels and the axle carried thereby, will not be 20 transmitted to the body and will not tend to tip or pitch the same, said body being permitted, by rocking about its axis with respect to the reaches, to maintain its substantially horizontal position, its only movement 25 being a slight vertical one in a substantially rectilinear direction.

The present invention has for its object to provide, in a spring suspension of the general type above referred to, a construction 30 wherein the forces transmitted to the body will be balanced so that rocking of the reaches in either direction, due to shocks imparted to the vehicle at either end, will result in the application to the body of balanced forces at opposite sides of the center, 35 of gravity thereof, tending solely to lift said body slightly in a substantially rectilinear direction without tilting the same.

The foregoing and other objects of the 40 invention, together with means whereby the same may be carried into effect, will best be understood from the following description of one form or embodiment thereof, illustrated in the accompanying drawings. It 45 will be understood, however, that the particular construction described and shown has been chosen for illustrative purposes merely, and that the invention, as defined by the claims hereunto appended, may be otherwise practised without departure from its spirit and scope.

In said drawings:

Fig. 1 is a side elevation, and Fig. 2 is

a plan view of a spring suspension constructed and operating in accordance with 55 the invention.

The principle of operation of a spring suspension of the general type of that to which the present case relates is fully explained in my prior application, Serial No. 504,160. For the purposes of the present description, this principle may be briefly outlined as follows:

In the ordinary vehicle, whether provided 65 with elliptical, semi-elliptical, or cantilever springs, the springs, are in effect, rigidly secured to the body or frame, and any shock or blow on a wheel, due to unevenness in the road, which causes the wheel to rise or fall suddenly, is communicated directly to 70 the body in effect at a point directly over the axle, and since this point is at an extreme distance from the center of gravity of the body, it has a maximum tendency to 75 cause pitching.

In the type of spring suspension to which the present invention relates, on the contrary, if the front wheel, for example, be raised, owing to an unevenness in the road, the tendency is for the spring reach to turn 80 about the pivot afforded by the rocker on which the body is supported, but not to rock the body. It thus tends to swing the rear end of the reach and rear axle downward about the pivot, so that a part of the blow 85 is absorbed by the rear spring and pneumatic tire on the rear wheel. Likewise, when the rear wheel goes over an obstruction or drops into a hole, the front spring member and front wheel receive the major part of 90 the reaction and the body is affected relatively little. In any event, any lifting force, or the resultant of such lifting forces as may be transmitted to the body as a result of 95 the rocking of the reaches, is applied to the body near the center of gravity thereof, so that there is small gyratory force acting upon the body eccentric to its center of gravity. The effect on the body is merely to lift the pivot, and consequently the body, vertically to a slight extent, and not to rock said body from front to back, so that the body is not given any pitching motion.

In one form of the invention shown and described in my prior application aforesaid, 105 the pivotal rocking connection between the

body and the reaches is located at one side of the center of gravity of the body, balancing springs being interposed between one of the axles and the body at the opposite side 5 of the center of gravity of the latter, whereby upward movement of said axle results in the application to the body, at opposite sides of the center of gravity thereof, of forces the moments of which are balanced. In accordance 10 with the present invention, a construction is provided wherein upward movement of the other axle, resulting in an upward force applied to the body at its pivotal connection with the reaches, is also accompanied 15 by an upward force applied to said body at the opposite side of the center of gravity thereof from said pivotal connection, thereby balancing about the center of gravity of the body all gyroscopic forces applied there- 20 to as the result of any rocking movement of the reaches under the influence of road shocks of any character when applied at either end of the vehicle.

Referring now to the drawings, there is 25 shown therein a pair of spring reaches to which the body frame 10 is connected by means of coaxial pivots 11 interposed between brackets 12 and 13 bolted or otherwise secured to the said body and reaches respectively. Each of the spring reaches is composed of a substantially rigid beam 14 having leaf spring extensions 15 and 16 at its forward and rear ends respectively. The extensions 15 are secured at their forward 35 ends, as by U-bolts 17, to the front axle 18 of the vehicle. The rear ends of the rear spring extensions 16 are pivotally connected, as at 19, to the adjacent inner or forward ends of semi-elliptical springs 20 supported 40 intermediate their ends by hangers 21 from the rear axle 22 of the vehicle. At their outer or rear ends, at the opposite side of the axle 22 from their connection with the spring extensions 16, the springs 20 are connected by 45 shackles 23 with the rear end of the body frame 10.

The axis of the pivots 11, about which the body 10 rocks with respect to the spring reaches, is located forward of the center of 50 gravity of the body, while the connection with the rear ends of the springs 20 (which constitute balancing springs) with the body is at the rear of the center of gravity thereof. The forward end of the body, at the opposite 55 side of its pivotal axis 11, is left free. Upward movement of the rear axle 22, therefore, causes opposed upward forces to be applied to the body at opposite sides of the center of gravity thereof, said forces balancing 60 one another and preventing rocking of the body when the reaches are rocked by such movement of the axle 22, as more fully explained in my prior application above referred to. In the present construction, however, when the spring reaches are rocked in 65

the opposite direction, by an upward movement of the front axle 18, the rear ends of said reaches will be forced downwardly, carrying with them the forward ends of the springs 20 with which they are connected. Said springs 20, being hung from the axle 22, constitute in effect, levers fulcrumed about the axis of said axle, so that a downward force applied to their inner or forward ends by the rear ends of the spring reaches will result in the application of an upward force to the rear end of the body by the outer or rear ends of said springs, acting through the shackles 23. It will, therefore, be seen that an upward force transmitted to the body through the axis 11 by reason of the upward movement of the axle 18 is accompanied by an upward force transmitted to the rear end of the body, and these forces, being applied at opposite sides of the center of gravity of the body, tend to stabilize the latter rather than to rock the same. By the arrangement shown, the body is therefore stabilized against shocks imparted to the vehicle at either end and accompanied by a rocking of the reaches in either direction, said body returning freely to its original position as soon as such disturbing forces are discontinued.

Besides the springs above referred to, an additional balancing spring is interposed between the body and each pivotal connection 19 between the springs 16 and 20. These are shown in the drawing in the form of quarter elliptic springs secured by brackets 25 to the body and connected at their ends by shackles 26 with the pivoted connections 19. The function of the springs 24 is to compensate for variations of the live load, particularly in the tonneau. The springs 24 are relatively light, being composed of a considerable number of relatively thin leaves the friction of which upon one another enables the same to function as shock absorbers, as more fully brought out in another application, filed May 28, 1923, Serial No. 641,934.

Since the springs 24 are of relatively small strength their reactive force on the body is not sufficiently great to interfere with the balanced effect of the springs above referred to, while at the same time they are sufficient to stabilize varying loads in the tonneau because their forces give double the effect of their pressure. That is to say, each spring 24 pressing down at the shackle 26 gives an equal upward force on the body, but the downward force at 26 acting through spring 20 in its turn gives approximately an equal upward force at 23.

The expression "spring reaches" is herein 125 employed as a comprehensive term to denote longitudinal members through which the body is supported from the axles and composed wholly or in part of springs. The term, therefore, is to be taken as including a 130

unitary spring as well as a reach composed of a substantially rigid beam to the ends of which are attached springs. It will be understood that when the spring reach is 5 constructed as last described, and as herein shown, the connection between the beam and the springs is a rigid one in the sense that there is no pivotal or other movable connection at this point.

10 The words "rear" and "front" and similar expressions are herein used as convenient illustrative terms, it being obvious that, although the construction shown is preferred for most purposes, the suspension might be 15 oppositely disposed, the pivotal connection between the body and the reaches being in the rear instead of in front of the center of gravity of the body, and the other parts being correspondingly arranged. These and 20 other modifications of the construction shown will, however, be readily apparent to those skilled in the art without discussion in detail.

Having thus described my invention, I 25 claim:

1. A spring suspension for vehicles including a spring reach connected to an axle of the vehicle and having a freely rocking connection intermediate its ends with the 30 vehicle body at one side of the center of gravity thereof, said spring reach extending beyond the opposite side of said center of gravity, and a spring fulcrumed intermediate its ends and operatively connected at 35 opposite sides of its fulcrum with said body and reach.

2. A spring suspension for vehicles including a spring reach having a rocking connection with the vehicle body at one side of the 40 center of gravity of the latter, and a balancing spring for the end of said body at the opposite side of the center of gravity, said balancing spring being fulcrumed intermediate its ends on an axle and being operatively 45 connected at opposite sides of its fulcrum with said body and reach, respectively.

3. A spring suspension for vehicles including a spring reach having a rocking connection with the vehicle body, a spring fulcrumed intermediate its ends and operatively 50 connected at opposite sides of its fulcrum with said body and reach, respectively, and a spring interposed between the body on the one hand and the connection between said 55 reach and first named spring on the other.

4. In a vehicle having a body and axles, a spring suspension including a spring reach having a rocking connection with the body at one side of the center of gravity of the 60 latter and connected at one end with the axle at the end of the body nearest said connection, and a spring fulcrumed intermediate its ends on the other axle and connected at its ends with the body and with the other 65 end of said spring reach, respectively.

5. In a vehicle having a body and axles, a spring suspension including a spring reach having a rocking connection with the body at one side of the center of gravity of the latter and connected at one end with the axle 70 at the end of the body nearest said connection, a spring fulcrumed intermediate its ends on the other axle and connected at its ends with the body and with the other end of said spring reach, respectively, and an 75 additional balancing spring for the body.

6. In a vehicle having a body and axles, a spring suspension comprising a pair of spring reaches and means connecting the same with said body and axles, said suspension including a spring member having a rocking connection intermediate its ends with the body and a spring member supported by an axle and movably connected with said first named spring member, and means 80 for connecting said last named spring member at both ends with the body to constitute a balancing spring. 85

7. In a vehicle having a body and axles, a spring suspension including a spring reach having a freely rocking connection with the body at one side of the center of gravity thereof and one end of the reach lying at the opposite side of said center of gravity, a spring member supported on an axle and 90 connected to said reach, and means for connecting said spring member with the body. 95

8. In a vehicle having a body and axles, a spring suspension including a spring member having a rocking connection with the body at one side of the center of gravity of the body, and one end of the member lying at the opposite side of said center of gravity, a spring member supported by the axle at 100 said opposite side of the center of gravity, and means for connecting said last named spring member with said first named spring member and with the body. 105

9. In a vehicle having a body and axles, a spring suspension comprising a pair of spring reaches one at each side of the body, each of said reaches comprising a spring member having a rocking connection with the body at one side of the center of gravity of the latter and a spring member supported by the axle at the opposite side of said center of gravity, said last named spring member being connected with said first named spring member at one side of said axle and with the body at the opposite side of said axle. 110 115

10. In a vehicle having a body and axles, a spring suspension comprising a pair of spring reaches, one at each side of the body, each of said spring reaches comprising a spring member having a rocking connection with the body at one side of the center of gravity of the latter and a spring member supported by the axle at the opposite side of said center of gravity, said last named spring member being connected with said 120 125 130

- first named spring member at one side of said axle, and means for connecting said last named spring member with the body at both sides of said axle.
- 5 11. In a vehicle having a body and axles, a spring suspension comprising a pair of spring reaches connected at their ends with the axles and a connection between said reaches and the body upon which the latter 10 is free to rock with respect to the former, each of said reaches including a spring member supporting the body, a semi-elliptical spring supported by an axle, one end of said spring supporting the adjacent end of the 15 body, a pivotal connection between the opposite end of said spring and the adjacent end of said spring member, and a spring interposed between said pivotal connection and the body.

12. In a vehicle having a body and axles, 20 a spring suspension comprising a pair of spring reaches connected at their ends with the axles and a connection between said reaches and the body upon which the latter 25 is free to rock with respect to the former, each of said reaches including a spring member supporting the body, a semi-elliptical spring supported by an axle, one end of said spring supporting the adjacent end of the 30 body, a spring secured to the body and having its end adjacent the other end of said semi-elliptical spring, and a shackle connecting the ends of said last named springs with each other and with the adjacent end of said 35 first named spring member.

In testimony whereof I affix my signature.

HENRY WEBB HYDE.
